POSITIONING CONTROL FOR HYDRAULIC MOTORS

Ransom Tyler, Greenfield, Wis., assignor to The Oilgear Company, Milwaukee, Wis., a corporation of Wisconsin

Application September 18, 1950, Serial No. 185,487

11 Claims. (Cl. 121—41)

1

This invention relates to apparatus for controlling the operation of hydraulic motors and it has as an object to provide a control which will cause a hydraulic motor to move a machine element or the like to a position which is determined by the adjustment of the control.

Another object is to provide a control which will cause a hydraulic motor to move an element into and positively hold it in a predetermined position.

The control is particularly adapted for effecting movement of the saw of a sawmill into selected positions but it may be used for many other purposes.

The invention is exemplified by the control shown schematically in the accompanying drawings in which the views are as follows:

Fig. 1 is a diagram of the hydraulic circuit of a motor to which the invention has been applied.

Fig. 2 is a plan view taken on the line 2—2 of Fig. 1 but drawn to a larger scale.

Figs. 3 and 4 are views showing the plunger or valve element of a control valve in positions different from those shown in Fig. 1.

Fig. 5 is a diagram of the electric circuit.

Fig. 6 is a diagram of the switches shown in Fig. 5.

The hydraulic motor may be of the reciprocating type and have its piston rod connected to the element to be moved or it may be of the rotary type and be connected to the element through a suitable drive such as a rack and pinion or a chain and sprocket drive. As shown, the hydraulic motor includes a stationary cylinder 1 and a piston 2 which is fitted in cylinder 1 and is connected by a piston rod 3 to a lug 4 fixed to a carriage 5 only a fragment of which has been shown as it forms no part of the invention.

Liquid for energizing motor 1—2 is supplied by a continuously driven pump 6 which draws liquid from a reservoir 7 and discharges it through a channel 8 into a control valve which may be of any suitable type. As shown, the control valve has a valve member or plunger 9 fitted in a valve body 10 which is connected by two channels 11 and 12 to opposite ends of cylinder 1. Communication between channel 8 and channels 11 and 12 is controlled by plunger 9 which also controls communication between those channels and an exhaust channel 13 which is connected to body 10 and discharges into reservoir 7.

Plunger 9 is urged to and normally held in its

2

central or neutral position by two springs 14 and 15, which are arranged in the opposite end portions of body 10, and it is adapted to be shifted in one direction or the other by one or the other of two solenoids S1 and S2 which are connected to plunger 9 by a suitable linkage 16.

The arrangement is such that, when neither of solenoids S1 or S2 is energized, valve plunger 9 is held in its neutral position by springs 14 and 15 in which position of plunger 9 channel 8 is connected through the interior of plunger 9 and body 10 to channel 13 so that pump 6 is bypassed and the ends of channels 11 and 12 are blocked by plunger 9 so that piston 2 cannot move.

When solenoid S1 is energized, it will shift plunger 9 toward the right into the position shown in Fig. 3 and then the liquid discharged by pump 6 will flow through channel 8, valve body 10 and channel 11 into the left end of cylinder 1 and cause piston 2 to move carriage 5 toward the right. The liquid ejected by piston 2 from the right end portion of cylinder 1 will flow through channel 12, valve body 10 and channel 13 into reservoir 7.

When solenoid S2 is energized, it will shift plunger 9 toward the left into the position shown in Fig. 4 and then the liquid discharged by pump 6 will flow through channel 8, valve body 10 and channel 12 into the right end of cylinder 1 and cause piston 2 to move carriage 5 toward the left. The liquid ejected by piston 2 from the left end portion of cylinder 1 will flow through channel 11, valve body 10 and channel 13 into reservoir 7.

Solenoids S1 and S2 are adapted to be energized selectively by the electric circuit shown in Fig. 5, a solenoid being energized in response to operation of one or the other of two limit switches LS1 and LS2 which form parts of the electric circuit and which are adjustable into selected positions in any suitable manner. As shown, switches LS1 and LS2 are adapted to be operated by a cam 17, which is movable with carriage 5 as by being carried by lug 4, and they are fastened to a slide 18 which is mounted upon a stationary guide 19. Slide 18 is connected by a rod 20 to a slide 21 which also is mounted upon guide 19 and preferably is frictionally held in adjusted positions by means not shown. Slide 21 is provided with a handle 22 for moving it and slide 18 along guide 19 and with a pointer 23 for indicating the position of switches LS1 and LS2 upon a stationary scale 24.

Each of limit switches LS1 and LS2 includes

a normally open contact *a*, a normally closed contact *b* and an operating button *c*, and each is a "microswitch" so that depressing button *c* only a few thousandths of an inch causes contact *a* to close and contact *b* to open.

When handle 22 is moved in either direction to a given position, motor 1—2 will move carriage 5 in the same direction and, as carriage 5 approaches a position corresponding to the position to which handle 22 was moved, cam 17 will momentarily depress the button at one limit switch and then depress the button of the second limit switch which will cause motor 1 to stop as will presently be explained. The two limit switches are so located in respect to each other and cam 17 is so shaped that cam 17 will depress the button of the second limit switch only an instant after it releases the button of the first limit switch.

As shown, buttons LS1^c and LS2^c have spherical ends, cam 17 has a knife edge to engage the spherical ends of the buttons, and switches LS1 and LS2 are slightly offset from each other, as indicated in Fig. 2, at such a distance that cam 17 will depress the button *c* of the second limit switch far enough to close its contact *a* just as soon as cam 17 allows the button *c* of the first limit switch to rise far enough to open its contact *a*.

Power for energizing solenoids S1 and S2 is supplied from a power line the two sides of which have been designated as L1 and L2. Solenoids S1 and S2 are controlled, respectively, by two contactor switches C1 and C2 each of which has a magnet *m* for operating it, three normally open contacts *a*, *b* and *c* and a normally closed contact *d*. Solenoid S1 has one end of its winding connected through a wire 30, contact C1^a and a wire 31 to power line L1 and the other end of its winding connected through a wire 32, contact C1^b and a wire 33 to power line L2. Solenoid S2 has one end of its winding connected through a wire 34, contact C2^a and a wire 35 to power line L1 and the other end of its winding connected through a wire 36, contact C2^b and a wire 37 to power line L2.

Contactor C1 and C2 are controlled in part by each other and in part by two relays R1 and R2. Relay R1 has three normally open contacts *a*, *b* and *c* and a magnet *m* for operating it. Relay R2 has two normally closed contacts *a* and *b*, two normally open contacts *c* and *d* and a magnet *m* for operating it, and it is of the type which is magnetically latched in its operating position as explained in Patent 2,297,339. That is, when an electric circuit is momentarily passed through a part of the magnet winding, the magnet will raise the contact in respect to the drawing, and, due to the residual magnetism in the magnet frame, will hold its contacts up until the frame is demagnetized by passing an electric current through the entire winding which will permit the contacts to drop. Relay R1 is controlled in part by a starting switch SS and in part by limit switches LS1 and LS2 which also control relay R2.

Magnet C1^m of contactor C1 has one end of its winding connected to power line L1 and the other end of its winding connected through a wire 38, contact C2^a, a wire 39, contact R2^c, a wire 40, contact R1^b, and a wire 41 to power line L2. Wire 40 is also connected through a wire 42, contact C1^c and a wire 43 to power line L2.

Magnet C2^m of contactor C2 has one end of

its winding connected to power line L1 and the other end of its winding connected through a wire 44, contact C1^d, a wire 45, contact R2^a, a wire 46, contact R1^a and a wire 47 to power line L2. Wire 46 is also connected through a wire 48, contact C2^c and a wire 49 to power line L2.

Magnet R1^m of relay R1 has one end of its winding connected to power line L1 and the other end of its winding connected through a wire 50, starting switch SS and a wire 51 to power line L2. Wire 50 is connected through a wire 52, contact R1^c, a wire 53, contact LS1^b, a wire 54, contact LS2^b and a wire 55 to power line L2.

Magnet R2^m of relay R2 has one end of its winding connected to power line L1 and it is connected intermediate the ends of its winding through a wire 56, contact R2^b, a wire 57, contact LS1^a and wire 55 to power line L2. The other end of the winding of magnet R2^m is connected through a wire 58, contact R2^d, a wire 59, contact LS2^a and wire 55 to power line L2.

Operation

If carriage 5 has been moved to the right, it will have stopped when cam 17 depressed limit switch LS2 and the contacts of the switches will be in the positions shown in Figs. 5 and 6.

To cause carriage 5 to move farther toward the right, limit switches LS1 and LS2 are moved toward the right by means of handle 22 until pointer 23 indicates upon scale 24 the position to which carriage 5 is to be moved. As soon as button LS2^c moves from beneath cam 17, switch LS2 will return to its normal position which will have no effect at this time. As switch LS1 moves toward the right, its button LS1^c will be depressed by cam 17 and cause it to establish a circuit (L1—R2^m—50—R2^b—57—LS1^a—55—L2) to effect operation of relay R2 to a position in which contacts R2^a and R2^b are open and contacts R2^c and R2^d are closed. Opening contact R2^b breaks the circuit through magnet R2^m and switch LS1 returns to its initial position as soon as its button LS1^c passes beyond cam 17 but relay R2 is magnetically latched in its operating position as previously explained.

Then closing starting switch SS establishes a circuit (L1—R1^m—50—SS—51—L2) to effect operation of relay R1 which will close its contacts R1^a, R1^b and R1^c. Contact R1^c establishes a circuit (L1—R1^m—50—52—R1^c—53—LS1^b—54—LS2^b—55—L2) to keep relay R1 operated when starting switch SS is released. Closing contact R1^a has no effect as contact R2^a is open. Closing contact R1^b establishes a circuit (L1—C1^m—38—C2^a—39—R2^c—40—R1^b—41—L2) to effect operation of contactor switch C1 which opens its contact C1^d and closes its contacts C1^a, C1^b and C1^c. Closing contact C1^c establishes a circuit (40—42—C1^c—43—L2) around contact R1^b to keep magnet C1^m energized when contact R1^b opens. Opening contact C1^a prevents switch C2 from being operated. Closing contacts C1^a and C1^b establishes a circuit (L1—31—C1^a—30—S1—32—C1^b—33—L2) to energize solenoid S1 which will shift valve plunger 9 to the position shown in Fig. 3 and then liquid will flow from pump 6 through channel 8, valve body 10 and channel 11 to the left end of cylinder 1 and cause piston 2 to move carriage 5 toward the right.

As carriage 5 approaches the position indicated by pointer 23, cam 17 will first depress limit switch LS1 the contact LS1^b of which will break the circuit through magnet R1^m which will per-

mit relay R1 to open its contacts R1^a, R1^b and R1^c. Opening contact R1^c prevents magnet R1^m from being reenergized when contact LS1^b closes. Opening contacts R1^a and R1^b has no effect as magnet C1^m is energized by the circuit through contact C1^c and as magnet C2^m is not energized at this time.

As carriage 5 continues toward the right, it will first permit limit switch LS1 to return to its normal position and then it will depress limit switch button LS2^c to close contact LS2^a and open contact LS2^b. The return of limit switch LS1 to its normal position and the opening of contact LS2^b have no effect at this time but closing contact LS2^a establishes a circuit (L1—R2^m—58—R2^a—59—LS2^a—55—L2) which causes relay R2 to close its contacts R2^a and R2^b and to open its contacts R2^c and R2^d.

Closing contacts R2^a and R2^b has no effect at this time. Opening contact R2^d breaks the circuit through magnet R2^m. Opening contact R2^c breaks the circuit through magnet C1^m which permits the contacts C1^a, C1^b and C1^c to open and contact C1^d to close. Closing contact C1^d has no effect at this time. Opening contact C1^c prevents magnet C1^m from being energized in response to relay R1 being closed. Opening contacts C1^a and C1^b deenergizes solenoid C1 which permits spring 15 to return valve plunger 9 to its central position in which position it cuts off delivery of liquid to cylinder 1 and blocks the end of channels 11 and 12 to prevent further movement of piston 2 so that carriage 5 is stopped and positively held in the position indicated upon scale 24 by pointer 23.

When carriage 5 stops, cam 17 will hold limit switch button LS2^c depressed and the other switches will be in their normal positions. That is the switch contacts will be in the positions indicated in Figs. 5 and 6 so that, if handle 22 is again moved toward the right, the above described cycle of operations will be repeated.

To cause carriage 5 to move toward the left, limit switches LS1 and LS2 are moved toward the left by means of handle 22 until pointer 23 indicates upon scale 24 the position to which carriage 5 is to be moved. As soon as button LS2^c moves from beneath cam 17 switch LS2 will return to its normal position which will have no effect at this time. After limit switches LS1 and LS2 have been moved to the desired position, starting switch SS is closed which causes relay R1 to close its contacts R1^a, R1^b and R1^c as previously explained. Closing contact R1^b has no effect as contact R2^c is open but closing contact R1^c establishes a circuit to hold relay R1 closed when switch SS is released as previously explained. Closing contact R1^a establishes a circuit (L1—C2^m—44—C1^d—45—R2^a—46—R1^a—47—L2) to energize magnet C2^m which causes contactor C2 to open its contact C2^d and to close its contacts C1^a, C1^b and C1^c. Opening contact C2^d has no effect but closing contact C2^c establishes a circuit (46—48—C2^c—49—L2) around contact R1^a to keep magnet C2^m energized when relay R1 opens. Closing contacts C2^a and C2^b establishes a circuit (L1—35—C2^a—34—S2—36—C2^b—37—L2) to energize solenoid S2 which will shift valve plunger 9 toward the left into the position shown in Fig. 4. Then liquid will flow from pump 6 through channel 8, valve body 10 and channel 12 to the right end of cylinder 1 and cause piston 2 to move carriage 5 toward the left.

As carriage 5 approaches the position indicated

by a pointer 23, cam 17 will first depress limit switch LS2 the contact LS2^b of which will break the circuit through magnet R1^m which will permit relay R1 to open its contacts R1^a, R1^b and R1^c. Opening contact R1^c prevents magnet R1^m from being reenergized when contact LS2^b opens. Opening contacts R1^a and R1^b has no effect as magnet C2^m is kept energized by the circuit through contact C2^c and as magnet C1^m is not energized at this time.

As carriage 5 continues to move toward the left, it will first permit limit switch LS2 to return to its normal position and then it will depress limit switch button LS1^c to close contact LS1^a and to open contact LS1^b. The return of limit switch LS2 to its normal position and the opening of contact LS1^b has no effect at this time but closing contact LS1^a establishes a circuit (L1—R2^m—56—R2^b—57—LS1^a—55—L2) to energize magnet R2^m which will cause relay R2 to open its contacts R2^a and R2^b and to close its contacts R2^c and R2^d. Closing contacts R2^c and R2^d has no effect as contacts R1^b, C1^c and LS2^a are open. Opening contact R2^b has no effect as relay R2 is kept operated by the residual magnetism in the frame of its magnet R2^m. Opening contact R2^a breaks the circuit through magnet C2^m which permits contactor C2 to close its contact C2^d and to open its contacts C2^a, C2^b and C2^c.

Opening contact C2^a and closing contact C2^d have no effect at this time but opening contacts C2^a and C2^b deenergizes solenoid S2 which permits spring 14 to return valve plunger 9 to its neutral position and thereby positively stop carriage 5 in the position indicated upon scale 24 by pointer 23 as previously explained.

If limit switches LS1 and LS2 are again moved toward the left, switch LS1 will return to its normal position as soon as its button LS1^c passes from beneath cam 17 and limit switch LS2 will be momentarily operated to close its contact LS2^a and open its contact LS2^b as its button L2^c passes beneath cam 17. The return of limit switch LS1 to its normal position and the opening of contact LS2^b will have no effect but closing contact LS2^a will establish the circuit through magnet R2^m to cause relay R2 to return to its normal position as previously explained. As soon as button LS2^c passes beyond cam 17, limit switch LS2 will return to its normal position which will have no effect. Then closing starting switch SS will initiate a cycle of operations to cause carriage 5 to be moved toward the left and stop in the position indicated by pointer 23 as previously explained.

By so locating limit switches LS1 and LS2 and so designing cam 17 that the contact *a* of one limit switch will be closed the instant after the contact *a* of the other limit switch opens, carriage 5 may be moved to and positively stopped in a position within a few thousandths of an inch of the position indicated by pointer 23.

The control described herein may be modified in various ways and adapted to various uses without departing from the scope of the invention which is hereby claimed as follows:

1. In a hydraulic transmission which includes a reciprocating motor for moving a load in opposite directions selectively and a source of motive liquid connected to said motor to energize the same, the combination of a piston valve connected between said motor and said source to control said motor, said valve being biased to a neutral position in which it prevents flow of liquid to or from said motor and being movable

into a first or a second operative position in which it directs liquid to one or the other end of said motor, a first and a second magnetic device adapted when energized selectively to move said valve into said first or said second positions respectively, an electric circuit for energizing said devices selectively including a starting switch, a control element movable in a path parallel to the path of said load and adapted to be moved in either of said directions into a selected position, means included in said circuit and responsive to movement of said control element in the first or the second of said directions for causing the first or the second of said devices to be energized in response to operation of said starting switch and thereby cause said motor to move said load in the first or the second of said opposite directions, respectively, limit switch means movable with said control element and adapted when operated to effect deenergization of the energized device, and a cam movable with said load and adapted in response to said load being moved into a position corresponding to said selected position to operate said limit switch means and thereby cause said energized device to be deenergized and permit said valve to return to its neutral position and cause said motor to stop said load in said corresponding position.

2. A control according to claim 1 in which said control element carries at a point remote from said load an indicator for indicating the position to which said load is to be moved.

3. A control according to claim 1 in which said electric circuit includes a relay for selecting which of said two devices shall be energized in response to operation of said starting switch and switch means movable with said element and operable by said cam to effect operation of said relay.

4. A control according to claim 1 including a slide which is movable in a path parallel to the path of said load and which supports said limit switch means in the path of said cam, and an element arranged at a distance from said switch means and connected to said slide for moving said switch means into selected positions.

5. In a hydraulic transmission which includes a source of motive liquid, a motor for moving a load, and two connections through one or the other of which liquid may flow from said source to said motor and cause it to move said load in one or the other of two directions, the combination of flow control means biased to a neutral position in which it prevents flow of liquid to said motor and movable into one or the other of two operative positions in which it directs liquid from said source to said motor through one or the other of said connections, a first magnetic device adapted when energized to move said flow control means into one operative position in which it directs liquid to said motor through one of said connections to cause said motor to move said load in the first of said directions, a second magnetic device adapted when energized to move said flow control means into another operative position in which it directs liquid to said motor through the other of said connections to cause said motor to move said load in the second of said directions, a control element movable in one or the other of said directions to a selected posi-

tion, an electric circuit for energizing said devices selectively including a starting switch, means included in said circuit and responsive to movement of said control element in the first or the second of said directions for causing the first or the second of said devices to be energized respectively in response to operation of said starting switch, said circuit including limit switch means movable with said element and adapted when operated to effect deenergization of the energized device, and a cam movable with said load and adapted in response to said load being moved to a position corresponding to said selected position to operate said limit switch means and thereby cause said device to be deenergized and permit said flow control means to return to its neutral position and cause said motor to stop said load in said corresponding position.

6. A control according to claim 5 in which said control element carries at a point remote from said load an indicator for indicating the position to which said load is to be moved.

7. A control for a transmission according to claim 6 in which said motor comprises a piston and a cylinder and said flow control means comprises a valve which when in its neutral position it blocks both ends of said cylinder.

8. A control according to claim 5 in which said flow control means is a valve which when in its neutral position it blocks both of said connections and thereby prevents said motor from moving or being moved by said load.

9. A control according to claim 5 in which said electric circuit includes a relay for selecting which of said two devices shall be energized in response to operation of said starting switch and switch means movable with said element and operable by said cam to effect operation of said relay.

10. A control according to claim 5 including a slide which is movable in a path parallel to the path of said load and which supports said limit switch means in the path of said cam, and an element arranged at a distance from said switch means and connected to said slide for moving said switch means into selected positions.

11. A control according to claim 10 including a stationary scale, and a pointer movable with said element for indicating upon said scale the position into which said load is to be moved.

RANSOM TYLER.
